FUSE-SETTING DEVICE.

1,079,885.

Specification of Letters Patent. Patented Nov. 25, 1913.

Application filed June 22, 1912. Serial No. 705,255.

To all whom it may concern:

Be it known that I, WILHELM SCHWARTZ, residing at Essen-on-the-Ruhr, Germany, a subject of the Emperor of Germany, have invented a certain new and useful Improvement in Fuse-Setting Devices, of which the following is a specification.

This invention relates to fuse setting devices for fuses that have two separate setting parts, each independent of the other.

The object of this invention is to provide a fuse setting device for fuses of this kind and particularly for combination shot fuses, wherein one adjustable part can be set to correspond to the distance of detonation and the other to the desired kind of firing, for instance hollow shell firing with bursting charge, impact firing with or without delayed action, which setting device is conveniently operated as a setting device for fuses having only one independently adjustable part.

Two embodiments of the present invention are illustrated in the drawings, showing in Figure 1 a front view of the first embodiment of this invention representing a fuse setting key together with the parts of the projectile necessary for explaining the invention; Fig. 2 a section along line 2—2 of Fig. 1, seen from the left; Fig. 3 a section along line 3—3 of Fig. 2, seen from above; and Fig. 4 a section along line 4—4 of Fig. 2, also seen from above; Fig. 5 a longitudinal axial section of the second embodiment representing a fuse setting machine; Fig. 6 a section along line 6—6 of Fig. 5, seen from above; Fig. 7 an end view of the machine partly in section, seen in the direction of arrow α in Fig. 5; and Fig. 8 a section along line 8—8 of Fig. 5, seen from above.

The fuse A, in both of the here illustrated embodiments, is a combination shot fuse and has in usual manner a fuse plate a^1 forming part of the fuse body, and seated thereon a time ring a^2 , which latter is adapted to be set to correspond to the desired detonating point or else for impact; and a head piece a^3 which can be turned independently of the time ring a^2 and serves for the purpose of setting the desired kind of firing. The revoluble head piece a^3 has three marks a^4 , a^5 , a^6 , see Fig. 4, to which corresponds a mark a^8 on the ring a^2 rigidly connected with the fuse body. When the revoluble

time ring a^2 has been set for a certain detonating point, the projectile will operate as shrapnel if the mark a^4 of the revoluble head piece a^3 registers with the mark a^8 ; and as hollow shell with bursting charge, if the mark a^5 registers with the mark a^8 . Should again the revoluble time ring a^2 be set for impact, the projectile will operate as hollow shell without delayed action, if either of the two marks a^4 and a^5 registers with the mark a^8 ; and if the mark a^6 registers with the mark a^8 as shell with delayed action.

The fuse setting key illustrated in Figs. 1 to 4 will now be described.

Three adjustable coaxial members C, D and E are revolubly mounted in the housing of the setting key, comprising two rings B and B^1 which are secured together. The setting member C is intended for engaging the fuse plate a^1 , the setting member D for engaging the time ring a^2 and the setting member E for engaging the head piece a^3 of the fuse A. Two spring actuated latches d^1 and e^1 for the notches in the time piece a^2 and the head piece a^3 are provided for coupling said fuse pieces respectively with the setting members D and E; while a rigid toe c^1 is arranged on the setting member C for coupling the latter with the fuse body, which toe c^1 is made to engage a suitable notch in the fuse plate a^1 . In the lower housing ring B^1 , which incloses the setting member C, a coupling stud b^2 is mounted to slide in radial direction, which stud is adapted to enter with its toe b^3 into the cut c^3 in the annular flange c^2 of the setting member C, so that the latter is secured to the housing B B^1 , when the toe b^3 is in engagement with the cut c^3 as is shown in Fig. 2. The stud b^4 of the stud b^2 is actuated by a spring b^5 , which tends to push the stud outward, and, by hand pressure on the head, the stud may be pushed in against the spring b^5 far enough into the housing B B^1 , that the toe b^3 will lie entirely within the room inclosed by the flange c^2 , whereby the setting member C will be set free.

Around the cylindrical portion of the setting member D are cut worm gear teeth d^2 , meshing with a self-locking worm F having a thumb wheel f^1 , which worm is revolubly mounted in the upper housing ring B. The function of the worm gear F d^2 is to bring the setting member D into the angular po-

sition corresponding to the desired distance of detonation. A scale d^3 visible through a window b^6 in the housing ring B, and a mark b^7 on the edge of the window b^6 , serve for reading the range to which the fuse is to be set. The setting member E is rigidly connected with a cap E², which reaches out beyond the housing B B¹ and is provided with a T-handle e³ and a flange e⁴, gripping over an inner flange b⁸ of the upper housing ring B.

In the inner flange b⁸ are drilled three holes b⁹ which may engage with a spring actuated latch pin e⁵, having a head e⁶, which pin is mounted on the flange e⁴, whereby the setting member E may be coupled with the housing B B¹ in three distinct angular positions. An index e⁷ on the flange e⁴ and three marks b¹⁰, b¹¹ and b¹² on the upper housing ring B are intended for indicating these angular positions. The angular distance between the marks b¹⁰, b¹¹ and b¹² corresponds to the angular distance between the marks a⁴, a⁵ and a⁶ on the fuse head piece a³. These three angular positions, wherein the setting member E may be adjusted relative to the housing B B¹, do therefore express the different kinds of firing in which the fuse may be set. Lastly the toe c¹ and two latches d¹ and e¹ are so located, that they have the same relative positions as the corresponding notches in the fuse, when the setting member C is locked by the coupling stud b² to the housing B B¹ and the fuse has the same adjustment as the setting key in accordance with the drawing.

In describing the use and manner of operation of this fuse setting key, it will be supposed that the different parts of the setting key, to commence with, have the positions indicated in the drawing, wherein the setting member E, as an instance, is coupled with the housing B B¹ in the angular position indicated by the mark b¹⁰ which corresponds to the shrapnel firing. Were it now desired to adjust the setting key for shell firing with bursting charge, the coupling between the setting member E and the housing B B¹ is then first detached by drawing out the latch pin e⁵ before the key is placed on the fuse; and the cap E² with the thereto rigidly connected setting member E is thereupon turned by using the head e⁶ of the latch pin e⁵ as handle, until the index e⁷ registers with the mark b¹¹, corresponding to the desired kind of firing. If now the latch pin is released, it will automatically enter the corresponding hole b⁹, so that the setting member E will be locked to the housing B B¹ in the angular position that corresponds to the desired kind of firing, and as a consequence also locked to the setting member C, which is intended for coupling with the fuse plate a¹. Hereupon the setting member D, which is intended for en-

gagement with the revoluble time ring a², has to be brought into an angular position relative to the setting member C, that corresponds to the desired distance of detonation. For this purpose the thumb-wheel f¹ has to be turned until the mark b⁷ registers with the division line on the scale d³, that corresponds to the desired distance of detonation, and this turning of the thumb-wheel is communicated by means of worm gear F d² to the setting member D. The adjustment of the setting key to the desired kind of firing (shell firing with bursting charge) as well as to the distance of detonation desired for this kind of firing, has now been accomplished.

The setting for any other kind of firing is done in a similar manner and need therefore no further explanation.

Now, in order to set the fuse, the setting key is placed on the fuse, as Fig. 2 shows, so that the toe c¹ of the setting member C will engage the notch in the fuse plate a¹ and the setting member C as a consequence is coupled to the fuse body. Usually, no engagement will then take place between the latches d¹ and e¹ and the corresponding notches in the fuse, but these latches will instead, as a rule, be pushed back in their apertures in the setting members D and E. After placing the setting key on the fuse and loosening the coupling between the setting member C and the housing B B¹ by pressing on the head b⁴ of the coupling stud b², the key is turned by the handle e³ once 360°. As now the setting member E, being rigidly connected with the T-handle e³, is coupled to the housing B B¹, by means of the latch pin e⁵, and the housing itself is coupled to the setting member D by means of the worm gear F d², all the here mentioned parts therefore turn together. During the turning the two latches d¹ and e¹ are sliding on the outer surface of their respective fuse parts a² and a³, until they snap into the notches of these fuse parts, thereby connecting said fuse parts with the respective setting members so that by continued turning of the fuse setting key, also the fuse part in question will be set. As soon as the fuse setting key has been turned 360°, the toe b³ of the coupling stud b², which, after the release of the head b⁴, was sliding on the inner surface of the annular flange e² during the turning, now snaps into the cut c³, thereby preventing any further turning. The setting members of the fuse setting key are then again situated in the same relative position as they had before the commencement of the turning.

As the two latches d¹ and e¹ in each case, during the described fuse setting operation, must arrive in engagement with the respective notches of the fuse parts a² and a³, these fuse parts will, under every circumstance, at

the end of the setting operation, be in engagement with the corresponding setting members D and E, and they will, therefore, have the same angular position as regards the fuse plate a^1 or with the thereto rigidly connected fuse part a^2 , which has been given to the setting members D and E, as regards the setting member C.

As soon as the fuse has been set, the fuse setting key is taken away; the latches d^1 , e^1 and the toe c^1 will then be disengaged in a well known manner, from the corresponding notches.

The second embodiment of the invention, illustrated in Figs. 5 to 8 representing the fuse setting machine, is also provided with three annular setting members, whereof, the first one G is intended for coupling with the fuse part a^1 , the second one H for coupling with the revoluble time ring a^2 and the third one J for coupling with the revoluble head piece a^3 of the fuse. The spring actuated latches g^1 , h^1 and i^1 engaging with corresponding notches in the fuse parts, are provided for coupling the setting members with the corresponding fuse parts, which members are coaxially mounted to revolve in the housing K. The setting member G is provided with a toothed circle g^2 , the setting member H with a toothed circle h^2 , and the setting member J with a toothed circle i^2 . The toothed circles g^2 , h^2 and i^2 are each in mesh with one of three bevel wheels M, N and P which are revoluble around a common axis in the housing K, and all of these bevel wheels have the same pitch cone. The inner bevel wheel M is in mesh with the toothed circle h^2 , the middle one N with the toothed circle g^2 and the outer one P with the toothed circle i^2 . The engagement of the toothed circle g^2 takes place at the upper part of the bevel wheel N, but the engagement of the toothed circles h^2 and i^2 , on the other hand, takes place at the lower part of the bevel wheels M and P, respectively. The ratio of the gearing of all three bevel gears (M h^2 , N g^2 and P i^2) is equal to 1. The inner bevel wheel M is rigidly connected with the crank M^1 , which constitutes the actuating member for setting the fuse. The crank M^1 is provided with a projection m^2 (see Fig. 6) which, in well known manner, has a cone-shaped notch m^3 for a similarly shaped spring actuated plunger k^2 mounted in the recess k^1 in the housing K; which plunger is adapted to yieldingly hold the crank in the position shown in Fig. 7. An abutment k^4 on the housing K, is provided for the latch h^1 of the setting member H connected with the crank M^1 through the bevel gear M h^2 , which abutment, for the purpose given in U. S. Patent No. 944,466 is arranged in such a manner, that the latch in co-operation with an arm h^3 , will automatically arrive in the inoperative position

represented in Fig. 6, when the crank M^1 has attained the mentioned angular position. The middle bevel wheel N is rigidly connected with a worm wheel N^2 , mounted on its hub n^1 , which worm wheel is inclosed by the box-shaped nave m^4 of the crank M^1 . A self-locking worm Q is in mesh with the worm wheel N^2 mounted on the crank nave m^4 , and this worm has an actuating crank q^1 , and is intended to give the desired angular position for responding to the desired distance of detonation to the setting member G, as regards the setting member H (by means of the bevel gearing N^2). For the purpose of reading the distance of detonation, a main scale r^5 is provided on a cone-shaped drum R, which is rigidly connected with a worm wheel R^1 running idle on the hub n^1 of the bevel wheel N. The worm wheel R^1 , which, similarly to the worm wheel N^2 , is inclosed in the box-shaped crank nave m^4 and possesses the same pitch diameter as the worm wheel N^2 , is in mesh with a worm T mounted on the crank nave m^4 , which worm has the same pitch as the worm Q, being connected to the latter by means of a set of spur gears t^1 , q^2 having the gearing ratio of 1. As will be evident from this description, the worm Q and the drum R will, therefore, always be in gearing connection, said worm Q serving for adjusting the desired distance of detonation, and the drum R carrying the corresponding main scale r^5 . The reading mark u^1 belonging to the scale r^5 , is placed on a revoluble ring U on the drum R, which ring is adjustable as regards the crank nave m^4 , for the purpose of making corrections. To adjust the ring U, there is provided a worm V revolubly but not slidably mounted in the crank nave m^4 , which worm meshes with teeth u^2 (see Fig. 5) on the ring U. The worm V is seated on a spindle V^1 which spindle can be axially displaced, compare particularly Fig. 8, and this spindle carries at one end, the crank v^2 and at its other end a spur wheel v^3 , which is intended to engage with another spur wheel q^3 , located on the shaft of the worm Q. In accordance with Patent No. 944,466, the device has been so arranged the worm V being slidably but non revolubly mounted on the spindle V^1 that the spur wheel v^3 is disengaged from the spur wheel q^3 , as long as the crank v^2 is at rest; and that by pushing the crank v^2 , inward the spindle V^1 first experiences a longitudinal displacement relative to the worm V and the crank nave m^4 , whereby the spur wheel v^3 is brought into engagement with the spur wheel q^3 ; and that only after the completion of engagement, the turning of the spur wheel, together with the worm V, can take place. The spindle V^1 being provided with a preferably square portion engaging in a similarly shaped aperture in one of the sides

of the crank nave m^4 is thus held in locked position by a helical spring around the spindle. From the above, it will be evident that a gearing connection exists between the 5 worm V and the setting member G, when the spur wheels v^3 and q^3 are in engagement, on the one hand, by means of the gearings v^3 q^3 , Q N^2 and N g^2 , so that the setting member G may be adjusted an 10 amount corresponding to the desired correction, by turning the worm V; and on the other hand by means of the gearings u^2 V, V^3 q^3 , q^2 t^1 , T R^1 , a gearing connection exists between the ring U and the drum R.

15 The ratio for the last mentioned gearing connection has been so selected, that the ring U will turn the same angle and in the same direction as the drum R, by turning the worm V, so that the position of the 20 mark u^1 as regards the main scale r^5 will not be changed. For reading the correction depending on the rotation of the ring U, a mark u^3 on said ring and a scale m^5 arranged opposite the same on the crank nave 25 m^4 , is provided.

The cone-shaped drum R incloses for the greater part a similarly cone-shaped drum P^1 rigidly connected to the hub of the bevel wheel P. At the outer edge, this drum P^1 has an annular flange p^2 which incloses the flange r^2 of the drum R. On this flange is arranged a spring actuated coupling pin p^3 with a head p^4 , which is adapted to engage with any one of three drilled holes r^3 in the 30 flange r^2 , compare particularly Fig. 7, so that the drum P^1 may be engaged in three separate angular positions with the drum R. To indicate these angular positions, a mark r^4 , Fig. 7, is supplied on the drum R, 35 and three marks p^5 , p^6 and p^7 are provided on the annular flange p^2 . The angular distance of the marks p^5 , p^6 and p^7 express the angular distance of the marks a^4 , a^5 and a^6 of the fuse part a^3 . The three angular 40 positions, wherein the drum P^1 as regards the drum R may be adjusted, will then express the different kinds of firings in which the fuse may be set, the drum P^1 being always in gearing connection with the setting member J, which is intended for engagement 45 with the fuse part a^3 , by means of the bevel gearing P i^2 . Lastly, the arrangement of the latches g^1 , h^1 and i^1 has been so arranged that they will have the same relative angular distance as the corresponding notches in 50 the fuse, when the crank M^1 is held by the plunger k^2 in the angular position presented in Fig. 7; and when furthermoré, the marks n^1 and n^3 register with the zero point of the 55 corresponding scales r^5 and m^5 , and the fuse has the same setting as the fuse setting machine.

In describing the use and manner of operation of this fuse setting machine, it will 60 be supposed that different parts of the fuse

setting machine to commence with, have the positions indicated in the drawing, wherein the drum P^1 , for instance, is coupled with the drum R in the angular position indicated by the mark p^5 which corresponds to the shrapnel firing. Were it now desired 70 to adjust the setting machine for shell firing with bursting charge, before introducing the shot into the setting machine, the coupling between the drums P^1 and R is 75 first detached by drawing off the coupling pin p^3 and thereupon the drum P^1 is turned, using the head p^4 of the coupling pin p^3 as a handle, until the mark p^6 registers with the mark r^4 of the drum R, corresponding 80 to the desired kind of firing. Through this turning the setting member J, by means of the bevel gearing P i^2 , receives the angular position corresponding to the desired kind 85 of firing as regards the setting member G, which has remained stationary during the described operation. If now, the coupling pin p^3 is released, it will automatically enter the corresponding hole r^3 in the flange r^2 so that the drum P^1 is now coupled to the 90 drum R.

The setting member G is now to be brought into the angular position as regards the setting member H, corresponding to the desired distance of detonation. For this 95 purpose, the handle q^1 is turned, and the turning thereof is transmitted to the setting member G by means of the worm gearing Q N^2 and the bevel gearing N g^2 . The drum R will simultaneously be turned by 100 means of the spur gearing q^2 , t^1 and the worm gearing T R^1 . The turning of the handle q^1 is continued until the division mark of the main scale r^5 , corresponding to the desired distance of detonation, registers with the mark u^1 . The setting member G has then received the angular position corresponding to the desired distance of detonation relative to the setting member H, in case no correction is necessary. The bevel 110 wheel P and the drum P^1 coupled to the drum R through the coupling pin p^3 , will, therefore, be turned simultaneously with the drum R, and as will be evident from the above, the turning of the bevel wheel P 115 will also take place with the same angular velocity as that of the bevel wheel N, but in the opposite direction. In consequence of this, the setting members G and J will turn in the same direction, and, similarly 120 to the bevel gearing N P, always the same angle, because the engagement of the toothed circle g^2 takes place at the upper half of the bevel wheel N, and the engagement of the toothed circle i^2 takes place at 125 the lower half of the bevel wheel P. The adjustment already given to the setting member J relative to the setting member G, corresponding to the desired kind of firing, will not be changed unless necessary, 130

through the adjustment of the setting member G to the desired distance of detonation.

Should a correction be necessary, that would be accomplished by turning the crank v^2 . The spindle V^1 —see Fig. 8—will then first be displaced so far in its axial direction, that the spur wheel v^3 will arrive in engagement with the spur wheel g^3 and then 5 partake, together with the worm V, in the rotation of the crank v^2 . The turning of the spindle V^1 is transmitted by means of the spur gearing v^3, g^3 to the worm Q and thence to the setting member G, similarly 10 to what happened during the main setting, on the one hand (by means of the train of gears N^2, N^1, g^2) and on the other hand (by means of the train of gears $g^2, t^1, T, R^1, R^2, p^1, P^1, P^2$) to the setting member J. Even in 15 this case, the setting members G and J will turn in the same direction and the same angle, so that the angular position corresponding to the kind of firing already given to the setting member J, relative to the 20 setting member G, will not be lost through the turning of the setting member G for the purpose of correction. The turning of the spindle V^1 is furthermore transmitted by means of the worm gearing V u^2 to the 25 ring U, and the latter will turn, as has already been mentioned, in the same direction and same angle as the drum R, so that the adjustment of the mark u^1 relative to the main scale r^5 , will not be altered through 30 the correcting adjustment. The turning of the crank v^2 will be continued until the mark u^3 of the ring U registers with the division mark of the scale m^5 , corresponding 35 to the desired correction.

40 The adjustment of the fuse setting machine for the desired kind of firing (hollow shell firing with bursting charge) and the desired distance of detonation for this kind of firing has herewith been accomplished.

45 The adjustment for any other kind of firing is accomplished in a similar manner and need not here be further explained. Now, in order to set the fuse, the projectile is first placed in the fuse setting machine, 50 see Fig. 5, without regard having to be taken to, in what position the notches on the fuse will be as regards the latches g^1, h^1 and i^1 . The crank M^1 is thereupon turned clockwise a complete revolution (see Fig. 7) 55 after the clutch k^2, m^2, m^3 has been disengaged by means of a powerful pressure on the crank handle. All of the bevel wheels will, therefore, partake of a turning of the crank M^1 because the bevel wheel M is 60 rigidly connected to the crank M^1 , and because furthermore, the bevel wheel N is locked to the crank nave m^4 through the self-locking worm gearing N^2, Q ; and because the bevel wheel P is coupled to the 65 drum R through the coupling pin p^3 ; and

also because the drum R is coupled to the crank nave m^4 through the self-locking worm gearing R^1, T . The turning of the bevel wheels M, N and P is in such a manner transmitted to the setting members G, H and J, that the setting members H and J each make a complete revolution in one direction, relative to the housing K, and the setting member G in the opposite direction. (The angular position of the setting member G as regards each of the setting members H and J will, therefore, be changed twice 360° .) During this operation, all the latches g^1, h^1 and i^1 will arrive in engagement with the notches of the corresponding fuse parts a^1, a^2 and a^3 , whereby the fuse parts will be coupled with the corresponding setting members.

At the end of the turning of the crank, the clutch k^2, m^2, m^3 will automatically set the crank in its original position, as illustrated in Fig. 7. The abutment k^4 will simultaneously bring the latch h^1 , in a well known manner, out of engagement with the corresponding notch of the revoluble time ring a^2 . All of the setting members of the fuse setting machine will now take up the previously given relative positions, and as a consequence, the corresponding fuse parts must, during the described setting operation, have been given the corresponding settings. At the end of the setting operation, the projectile is taken away from the fuse setting machine; the latches g^1, h^1 and i^1 will then automatically be disengaged, in the usual manner, from the notches of the corresponding fuse parts.

I claim:

1. A setting device for fuses with two setting parts independent of each other, comprising three setting members, the first setting member being constructed to engage the body of the fuse; the second setting member constructed to engage the one, and the third setting member the other, of the independent setting parts of the fuse; each of said setting members adapted to engage the respective fuse parts only at a certain angular position relative to each other; the angular positions, of said second and third setting members relative to the first setting member being adapted to be changed at least once 360° during the setting operation of the fuse, after the angular position corresponding to the desired setting has been given to said second and third setting members relative to the first setting member.

2. A setting device for fuses with two setting parts independent of each other, comprising three setting members, the first setting member being constructed to engage the body of the fuse; the second setting member constructed to engage the one, and the third setting member the other, of the independent setting parts of the fuse; each of

said setting members adapted to engage the respective fuse parts only at a certain angular position relative to each other; the angular positions of said second and third setting members relative to the first setting member being adapted to be changed at least once 360° during the setting operation of the fuse, counted from that angular position of said three setting members when all three 10 are in engagement with their respective fuse parts.

3. A setting device for fuses, with two setting parts independent of each other, comprising three setting members, the first setting member being constructed to engage the body of the fuse; the second setting member constructed to engage the one and the third setting member the other of the independent setting parts of the fuse; a housing 15 for the setting members and an automatic clutch between said housing and said first setting member; said second and third setting members being angularly adjustable relative to said housing, an amount 20 corresponding to the desired setting of said two setting parts of the fuse; said clutch being released by hand when the fuse is inserted 25 into the fuse setting device, and automatically brought into action at the moment the 30 desired angular position relative to the fuse body has been attained.

4. A setting device for fuses with two setting parts independent of each other, comprising three setting members, the first setting member being constructed to engage the body of the fuse; the second setting member constructed to engage the one and the third setting member the other of the independent setting parts of the fuse; a housing 35 wherein said setting members are revolubly mounted and an automatic clutch between said housing and said first setting member, said first setting member being adapted to engage the fuse body at a certain 40 angular position relative to the fuse; said second and third setting members being angularly adjustable within said housing corresponding to the desired setting; and said automatic clutch, coupling together 45 said housing and said first setting member at a certain predetermined angular position of said first setting member relative to the housing.

5. A setting device for fuses with two setting parts independent of each other, comprising a housing; three independently revoluble setting members mounted in the housing; the first of said setting members having a notch, a spring actuated plunger 55 in said housing, tending to engage said notch and adapted to be released by hand; a toe on said first setting member adapted to engage a recess in the fuse body; a spring actuated plunger in the second of said setting members adapted to engage a notch in

the first of the independent setting parts of the fuse; a hand operated worm mounted to rotate in said housing and worm teeth meshing therewith on said second setting member; a spring actuated plunger in the third of said setting members adapted to engage a notch in the second of the independent setting parts of the fuse; a spring actuated plunger in said third setting member and said housing having a plurality of apertures, 70 said last named plunger adapted to automatically engage any one of said apertures, whereby said housing and said third setting member will be locked together, and said plunger being constructed to be withdrawn 75 by hand; a handle on said third setting member for actuating the fuse setting device for setting the fuse.

6. A setting device for fuses with two setting parts independent of each other, comprising three setting members, the first setting member being constructed to engage the body of the fuse; the second setting member constructed to engage the one, and the third setting member the other, of the independent setting parts of the fuse; each of said setting members adapted to engage the respective fuse parts only at a certain angular position relative to each other; the angular position of said first setting member relative to said second and third setting members being adapted to be changed, during the fuse setting operation, twice 360° , after said two last named setting members have been angularly adjusted for the desired 90 setting relative to the first setting member. 95

7. A setting device for fuses with two setting parts independent of each other, comprising three setting members, the first setting member being constructed to engage the body of the fuse; the second setting member constructed to engage the one and the third setting member the other of the independent setting parts of the fuse; a housing wherein said setting members are 100 revolubly mounted; a gearing connection between said first setting member and said third setting member, said gearing connection constructed to revolve said first and third setting members the same angle and in 105 the same direction, when said first setting member is being turned to adjust the device for the angular position to be given the first independent setting part of the fuse. 110

8. A setting device for fuses with one setting part for the distance of detonation and a second setting part independent of the first for the desired kind of firing; comprising one setting member for engaging the fuse body; a second setting member for engaging the first and a third setting member for engaging the second independent setting part of the fuse; a housing wherein said three setting members are revolubly mounted; three bevel wheels, having the same 115 120 125 130

pitch cone, revolubly mounted in said housing; a toothed circle on each of said three setting members, meshing respectively with one of said three bevel wheels; gearing connection between said three bevel wheels whereby said first setting member is made to turn in opposite direction to that of the second and third setting members during the operation of the device.

10 9. A setting device for fuses with one setting part for the distance of detonation and a second setting part independent of the first for the desired kind of firing; comprising one setting member for engaging the fuse body; a second setting member for engaging the first and a third setting member for engaging the second independent setting part of the fuse; a housing wherein said three setting members are revolvably mounted; three bevel wheels, having the same pitch cone, revolvably mounted in said housing; a toothed circle on each of said three setting members; the inner bevel wheel being in mesh with the teeth of said second setting member; an operating handle rigidly connected with said smallest bevel wheel; the middle bevel wheel being in mesh with the teeth of said first setting member; a spring actuated and hand set clutch for locking said middle bevel wheel at any angle relative to said operating handle; the outer bevel wheel being in mesh with the teeth of said third setting member; an actuating member and a clutch for locking said outer bevel wheel in a plurality of angular positions to said actuating member; said outer bevel wheel turning the same angle but in the opposite direction as said middle bevel wheel, during the turning of said middle bevel wheel.

40 10. A setting device for fuses with one setting part for the distance of detonation and a second setting part independent of the first for the desired kind of firing; comprising one setting member for engaging the fuse body; a second setting member for engaging the first and a third setting member for engaging the second independent setting part of the fuse; a housing wherein said 45 three setting members are revolvably mounted; three bevel wheels, having the same pitch cone, revolvably mounted in said housing; a toothed circle on each of said three setting members; the inner bevel wheel 50 being in mesh with the teeth of said second setting member; an operating handle rigidly connected with said smallest bevel wheel; the middle bevel wheel being in mesh with the teeth of said first setting member; 55 a spring actuated and hand set clutch for locking said middle bevel wheel at any angle relative to said operating handle; the outer bevel wheel being in mesh with the teeth of said third setting member; an 60 actuating member and a clutch for locking 65

said outer bevel wheel in a plurality of angular positions to said actuating member; a worm revolubly mounted in said operating handle, a worm wheel in mesh with said worm rigidly connected with middle bevel wheel; a second worm revolubly mounted in said operating handle, a second worm wheel in mesh with said worm rigidly connected with said actuating member; gearing connection between said two worms, whereby said second worm wheel is compelled to turn the same angle but in opposite direction as the first worm wheel by operating the first worm.

11. A setting device for fuses with one setting part for the distance of detonation and a second setting part independent of the first for the desired kind of firing; comprising one setting member for engaging the fuse body; a second setting member for engaging the first and a third setting member for engaging the second independent setting part of the fuse; a housing wherein said three setting members are revolubly mounted; three bevel wheels, having the same pitch cone, revolubly mounted in said housing; a toothed circle on each of said three setting members; the inner bevel wheel being in mesh with the teeth of said second setting member; an operating handle rigidly connected with said smallest bevel wheel; the middle bevel wheel being in mesh with the teeth of said first setting member; a spring actuated and hand set clutch for locking said middle bevel wheel at any angle relative to said operating handle; the outer bevel wheel being in mesh with the teeth of said third setting member; an actuated member and a clutch for locking said outer bevel wheel in a plurality of angular positions to said actuating member; a worm revolubly mounted in said operating handle, a worm wheel in mesh with said worm rigidly connected with said middle bevel wheel; a second worm revolubly mounted in said operating handle, a second worm wheel in mesh with said worm rigidly connected with said actuating member; gearing connection between said two worms, whereby said second worm wheel is compelled to turn the same angle but in opposite direction as the first worm wheel by operating the first worm; a third worm revolubly mounted in said operating handle; a manually operated, axially displaceable spindle for said third worm; a vernier-ring revolubly mounted on said operating handle; a toothed circle on said vernier-ring in mesh with said third worm; gearing between said spindle and said first worm; said gearing being temporarily connected for turning said vernier-ring when axially displacing said spindle only, said spindle being normally locked against turning.

12. A setting device for fuses with two setting parts independent of each other, comprising three coaxial setting members, the first setting member being constructed to engage the body of the fuse; the second setting member constructed to engage the one, and the third setting member the other of the independent setting parts of the fuse; and means for establishing an angular position of said second and third setting member relative to the first setting member corresponding to the desired setting of said two setting parts of the fuse.
13. A setting device for fuses with two setting parts independent of each other, comprising two coaxial setting members constructed to engage said independent fuse parts respectively; a housing for said setting members; and an automatic clutch for coupling said housing to the body of the fuse; said setting members being angularly adjustable relatively to said housing an amount corresponding to the desired setting of said two setting parts of the fuse and said clutch being released by hand when the fuse is inserted into the fuse setting device and automatically brought into action at the moment the desired angular position relative to the fuse body has been attained.
14. A setting device for fuses with two setting parts independent of each other, comprising three coaxial setting members, the first setting member being constructed to engage the body of the fuse; the second setting member constructed to engage the one, and the third setting member the other, of the independent setting parts of the fuse; means for establishing an angular position of said second and third setting member relative to the first setting member corresponding to the desired setting of said two setting parts of the fuse; an operating member for adjusting the fuse and means actuated by said operating member for altering said angular position twice 360°.
15. A setting device for fuses with two setting parts independent of each other, comprising a housing, a setting member revolvably mounted in said housing and constructed to engage the body of the fuse, a second setting member coaxial with said first setting member and constructed to engage one of said independent setting parts of the fuse, means for locking said second setting member relatively to the housing in a predetermined angular position, a third setting member coaxial with said first and second setting member and constructed to engage the other of said independent setting parts of the fuse, means for adjusting said third setting member relatively to said first setting member an amount corresponding to the desired setting of the fuse part engaged by said third setting member, means for adjusting said first setting member relatively to said second setting member an amount corresponding to the desired setting of said first setting member, means establishing connection between said first and third setting member to revolve said third setting member the same angle and in the same direction as said first setting member when being adjusted for the angular position to be given said first-named independent fuse part, an operating member for adjusting the fuse and means actuated by said operating member for altering the angular position assumed by said second and third setting member relatively to said first setting member twice 360°.
16. A setting device for fuses with one setting part for the distance of detonation and a second setting part independent of the first for the desired kind of firing; comprising a housing, a setting member revolvably mounted in said housing and constructed to engage the body of the fuse, a second setting member coaxial with said first setting member and constructed to engage said first setting part of the fuse, a third setting member coaxial with said first and second member and constructed to engage said second setting part of the fuse, an operating member rotatably mounted in said housing for adjusting the fuse, releasable means for locking said operating member relatively to the housing in a predetermined angular position, three bevel wheels coaxial with said operating member and having the same pitch cone, the first of said bevel wheels being rigidly connected with said operating member, means for adjusting the second bevel wheel relatively to said operating member an amount corresponding to the desired setting of said first setting part of the fuse, a rotatable body coaxial with said bevel wheels, means establishing positive connection between said rotatable body and said second bevel wheel causing said body to turn the same angle but in the opposite direction as said second bevel wheel when being adjusted relative to said operating member, releasable means for locking the third bevel wheel in a plurality of angular positions relatively to said rotatable body, a gearing connection between said first bevel wheel and said second setting member, another gearing connection between said second bevel wheel and said first setting member, and a third gearing connection between said third bevel wheel and said third setting member, said gearing connections causing said second third setting member to be turned the same angle but in opposite direction as said first setting member when said three bevel wheels turn in unison.
17. A setting device for fuses with one setting part for the distance of detonation and a second setting part independent of the first for the desired kind of firing; comprising

ing a housing, a setting member revolubly mounted in said housing and constructed to engage the body of the fuse, a second setting member coaxial with said first setting member and constructed to engage said first setting part of the fuse, a third setting member coaxial with said first and second member and constructed to engage said second setting part of the fuse, an operating member rotatably mounted in said housing for adjusting the fuse, releasable means for locking said operating member relatively to the housing in a predetermined angular position, three bevel wheels coaxial with said operating member and having the same pitch cone, the first of said bevel wheels being rigidly connected with said operating member, a worm wheel rigidly connected with said second bevel wheel, a worm revolubly mounted on said operating member and being in mesh with said worm wheel for adjusting said second bevel an amount corresponding to the desired setting of said first setting part of the fuse, a second worm wheel coaxial with said operating member and having the same pitch cone, the first of said bevel wheels being rigidly connected with said operating member, a worm wheel rigidly connected with said second bevel wheel, a worm revolubly mounted on said operating member and being in mesh with said worm wheel for adjusting said second bevel an amount corresponding to the desired setting of said first setting part of the fuse, a second worm wheel coaxial with said bevel wheels, a second worm revolubly mounted on said operating member and being in mesh with said second worm wheel, a gearing connection between said two worms, whereby said second worm wheel is compelled to turn the same angle but in the opposite direction as the first worm wheel by operating the first worm, releasable means for locking the third bevel wheel in a plurality of angular positions relatively to said second worm wheel, a gearing connection between said first bevel wheel and said second setting member, another gearing connection between said second bevel wheel and said first setting member, a third gearing connection between said third bevel wheel and said third setting member, said gearing connections causing said second and third setting member to be turned the same angle but in opposite direction as said first setting member when said three bevel wheels turn in unison, a third worm revolubly mounted on said operating member, a manually operated, axially displaceable spindle for said third worm, means normally locking said spindle against turning and adapted to be released by axially displacing the spindle, a gearing connection between said spindle and said first worm, said gearing connection comprising two gearing members normally being out of engagement and adapted to automatically engage each other when said spindle is axially displaced for releasing said locking means, an annular reading off member revolubly mounted on said operating member, and a toothed arc on said reading off member in mesh with said third worm, whereby said reading off member is caused to turn the same angle and in the same direction as said second worm wheel when said spindle is turned.

18. A setting device for fuses with one setting part for the distance of detonation and a second setting part independent of the first setting part for the desired kind of firing; comprising a housing, a setting member revolubly mounted in said housing and constructed to engage the body of the fuse, a second setting member coaxial with said first setting member and constructed to engage said first setting part of the fuse, a third setting member coaxial with said first and second member and constructed to engage said second setting part of the fuse, an operating member rotatably mounted in said housing for adjusting the fuse, releasable

means for locking said operating member relatively to the housing in a predetermined angular position, three bevel wheels coaxial with said operating member and having the same pitch cone, the first of said bevel wheels being rigidly connected with said operating member, a worm wheel rigidly connected with said second bevel wheel, a worm revolubly mounted on said operating member and being in mesh with said worm wheel for adjusting said second bevel an amount corresponding to the desired setting of said first setting part of the fuse, a second worm wheel coaxial with said bevel wheels, a second worm revolubly mounted on said operating member and being in mesh with said second worm wheel, a gearing connection between said two worms, whereby said second worm wheel is compelled to turn the same angle but in the opposite direction as the first worm wheel by operating the first worm, releasable means for locking the third bevel wheel in a plurality of angular positions relatively to said second worm wheel, a gearing connection between said first bevel wheel and said second setting member, another gearing connection between said second bevel wheel and said first setting member, a third gearing connection between said third bevel wheel and said third setting member, said gearing connections causing said second and third setting member to be turned the same angle but in opposite direction as said first setting member when said three bevel wheels turn in unison, a third worm revolubly mounted on said operating member, a manually operated, axially displaceable spindle for said third worm, means normally locking said spindle against turning and adapted to be released by axially displacing the spindle, a gearing connection between said spindle and said first worm, said gearing connection comprising two gearing members normally being out of engagement and adapted to automatically engage each other when said spindle is axially displaced for releasing said locking means, an annular reading off member revolubly mounted on said operating member, and a toothed arc on said reading off member in mesh with said third worm, whereby said reading off member is caused to turn the same angle and in the same direction as said second worm wheel when said spindle is turned.

The foregoing specification signed at Bar-
men, Germany, this 1st day of June, 1912.

WILHELM SCHWARTZ. [L. S.]

In presence of—

HELEN NUFER,
ALBERT NUFER.
